DISPLAY HOLDER FOR TOOTHBRUSH OR LIKE ARTICLE

Richard M. Hyman, Iowa City, Iowa, assignor, by mesne assignments, to Weco Products Company, a corporation of Delaware

Filed Oct. 17, 1960, Ser. No. 62,510

Term of patent 14 years

(Cl. D58—12)

Fig. 1

Fig. 2

I claim:

The ornamental design for a display holder for toothbrush or like article, as shown.
